BOLT ANCHOR

Alfred W. Gelpcke, Brooklyn, N. Y., assignor to
The Rawlplug Company, Inc., New York, N. Y.

Application April 2, 1932. Serial No. 602,658

5 Claims. (Cl. 72—105)

This invention relates to means for fastening bolts, studs, or the like into concrete, brick, or other masonry, whereby fixtures of various kinds may be fastened by the bolts or studs.

5 In my Patent 1,852,297, issued April 5, 1932, there is disclosed a unitary reversible bolt-anchor which has many advantages as set forth in said patent.

My present invention is directed to a modified 10 form of two-piece bolt-anchor so constructed as to be a unitary device, and one which may be reversibly installed in the hole made to receive it.

In the drawing,

Figure 1 is an end-view of the complete device.

15 Figure 2 is a part-elevational and part-sectional view of the same.

Figure 3 is an end-view of a modified form of the device.

20 Figure 4 is a part-elevational and part-sectional view of the modified form of the device.

By reference to the drawing, it will be seen that the bolt-anchor comprises a strip 1 of metal both ductile and malleable, arranged in the form of a spiral which is preferably substantially uniform 25 in its diameter from one end of the anchor to the other. Preferably the convolutions terminate in flat, parallel flanges 2 and 3. This spirally-arranged member may be made from rolled stock having the desired cross-sectional area, or it may 30 be cast. In either case, it serves as a framework for carrying between the spirals an expandable metal 4 which is preferably of lead moulded into the spiral framework, but so as to leave a bore 5 through the anchor to receive a bolt or 35 stud.

In the form shown in Figure 4, the spirally-arranged member 1 has a different cross-sectional area than that shown in Figure 2, but otherwise what has been said with respect to Figure 2, applies to the anchor shown in Figure 4.

40 In Figure 4, however, the spirally-wound member 1 has its convolutions ending in a relatively sharp biting edge 6, which assists in causing the spiral to grip into the masonry or concrete as the 45 device is hammered into position.

In the use of these unitary reversible anchors, they are dropped into a hole in the masonry and hammered into gripping position in the manner set forth in my patent previously referred to, but 50 it may be noted that in the construction herein disclosed, as the spirals are forced toward each other by the calking blows, the lead is forced from between the spirals into engagement with the side-walls of the hole in the concrete or other 55 masonry, and likewise, the spirals themselves, as

they are driven together, also seize the side-walls of the hole and thereby function jointly with the expandable metal to make a secure connection between the anchor and the material in which they are placed.

I form the frame-member 1 of aluminum, although I do not wish to be limited to this particular material, but since aluminum is light and has the necessary strength, it is admirably suited for the purpose and has the advantage of reducing the cost of shipping, as well as lightening the tool-bag of the workman, and is therefore preferable to use.

Having thus described my invention, what I claim is:

1. A bolt-anchor comprising a single spirally-formed member extending the full length of the anchor and terminating in flanges, and expandable metal lying between the spirals but leaving a central hole for the bolt.

2. A unitary bolt-anchor comprising a strip of ductile and malleable metal arranged in a spiral the outer periphery of which terminates in a relatively sharp edge and carrying expandable metal between the turns of the spiral.

3. A cylindrically-shaped reversible bolt anchor comprising a member formed in convolutions to encircle a bolt for the normal length of the anchor, said convolutions having a relatively sharp biting edge and expandable metal between 85 said convolutions.

4. A unitary two-piece bolt-anchor comprising a spirally-arranged metallic frame having a continuous relatively sharp biting edge and adapted to be compressed and expandable metal carried 90 by the spirals of the frame.

5. A bolt anchor comprising a single spirally-formed member extending the full length of the anchor and terminating in flanges, and expandable metal lying between the spirals and forming 95 therewith and with said flanges a central hole for a bolt, the inside and outside radii of the flanges, spirals and expandable metal being correspondingly the same.
